UNITED STATES PATENT OFFICE.

THOMAS DAVIS, OF TRENTON, NEW JERSEY.

DESIGN FOR A DISH.

SPECIFICATION forming part of Design No. 16,708, dated May 25, 1886.

Application filed April 2, 1886. Serial No. 197,592. Term of patent 3½ years.

To all whom it may concern:

Be it known that I, THOMAS DAVIS, a citizen of the United States, residing at Trenton, in the county of Mercer and State of New Jersey, have invented and produced a new and original Design for Cover Vegetable-Dishes, of which the following is a specification, reference being had to the accompanying drawing, forming part thereof.

10 The drawing affords a perspective view of the dish with the lid or cover in place.

The leading features of my design consist in the vertically-fluted offset on the outer sides of the lid, and in the projecting feet joined by 15 a plain extended base, above which is a fluted recess, the whole producing the effect of a dish set in a metal stand or base.

10 A is the lid, near the edges of which is the vertically-fluted offset B. The body of the dish C has at its corners projecting feet D D, which are joined by the extended base E. Above the base E is the fluted recess G, merg-

ing at its upper side into the outwardly-curving bowl or body of the dish C.

What I claim is—

25 1. The design for a covered vegetable dish, consisting of the lid or cover A, having upon its outer side, near the edges, the vertically-fluted offset B, and the body of the dish C, having projecting feet D D, joined by an extended 30 base, E, having above it the fluted recess G, merging above into the outwardly-curving body of the dish C, as shown.

2. The design for a vegetable-dish, consisting of the body C, having projecting feet D D, 35 joined by an extended base, E, having above it the fluted recess G, merging above into the outwardly-curving body of the dish C, as shown.

THOMAS DAVIS.
